UNITED STATES PATENT OFFICE.

WILLIAM C. DAY, OF RUMFORD FALLS, MAINE.

DESIGN FOR A NUTMEG-GRATER CASING.

SPECIFICATION forming part of Design No. 31,437, dated August 22, 1899.

Application filed July 17, 1899. Serial No. 724,196. Term of patent 14 years.

To all whom it may concern:

Be it known that I, WILLIAM C. DAY, of Rumford Falls, in the county of Oxford and State of Maine, have invented and produced a new and original Design for a Nutmeg-Grater Casing, of which the following is a specification, reference being had to the accompanying drawing, forming a part thereof.

The drawing represents a perspective view of a nutmeg-grater embodying my design.

The distinguishing feature of my design is the shape of the outer casing *a*, constituting the visible body of the nutmeg-grater. Said casing has the appearance of two truncated

cones placed with their smaller ends together, ¹⁵ making a waist or contracted portion *2* and two flaring end portions *3* and *4*, the conical portion *4* being considerably shorter than the conical portion *3*.

I claim—

The design for a nutmeg-grater, substantially as shown and described.

In testimony whereof I have affixed my signature in presence of two witnesses.

WILLIAM C. DAY.

Witnesses:

C. F. BROWN,
E. BATCHELDER.
